UNITED STATES PATENT OFFICE

JOHN B. TEESDALE, OF GRAND RAPIDS, MICHIGAN

ROTARY PUMP

Application filed September 7, 1928. Serial No. 304,592.

This invention relates to a fluid pressure pump of the rotor type.

The main objects of this invention are to provide an improved construction of rotary pump which will put up a high pressure without objectionable pulsations to the discharge stream; to provide an improved construction of rotary piston which will discharge at high pressure and which will not permit the discharge fluid to "shoot back" around the rotor; to provide a pump of this character which will have a relatively even and smooth discharge flow and to provide a generally improved and simplified construction which will meet with necessary requirements hitherto unattained.

An illustrative embodiment of this invention is shown in the accompanying drawings in which:—

20 Fig. 1 is a vertical longitudinal medial sectional view of my improved pump.

Fig. 2 is a sectional view taken on the line 2—2 of Fig. 1.

25 Fig. 3 is a sectional view taken on the line 3—3 of Fig. 1, with the lower portion thereof broken away.

Fig. 4 is a sectional view taken on the line 4—4 of Fig. 3.

30 Fig. 5 is a sectional view of a modified form of the device, taken on the line 5—5 of Fig. 6.

Fig. 6 is a sectional view taken on the line 6—6 of Fig. 5.

35 Fig. 7 is an enlarged view of one of the rotary pistons showing the different curvatures of the peripheral face thereof.

Fig. 8 is a plan view of a modified form of spring means.

40 In the constructions shown in the drawings, the housing of the pump within which the working parts are contained comprises a base member 1 drilled to receive intake and discharge pipes 2 and 3 respectively which communicate with intake and discharge passageways 4 and 5 respectively formed in the base housing 1. The housing 1 is provided with an elongated cylindrical neck portion 6 adapted to be embraced by clamps or the like for mounting the pump.

45 An axial bore extends through the housing

1 and neck portion 6 to receive a drive shaft 7, the outer end 8 of which extends without the housing in order that it may be attached to a suitable source of power. The end 8 of the shaft is of reduced size and the outer end of the axial bore is enlarged so as to receive a quantity of packing 9 which is retained by a gland 10 and an interiorly threaded cap 11 which engages an exteriorly threaded reduced end of the neck 6.

50 As shown most clearly in Figs. 1 and 4 of the drawings, the inner end of the packing 9 abuts against a shallow cup-shaped washer 12 which surrounds the shaft at a point closely adjacent to where it is reduced in size so as to form an annular opening or sump 13 which surrounds the shaft and into which fluid from the pump, which leaks along the shaft, may drain.

55 Means are provided for draining the sump 13 and comprise a passageway 14 drilled in the housing at an angle to the axis of the shaft 7 with the inner end thereof communicating with the sump. The outer end of the passageway is closed by a threaded plug 15 and a short passageway 16 is drilled from the intake passageway 4 to the drain passageway 14 so as to provide communication between the intake 4 and the sump 13.

60 The end of the housing opposite the neck 6 terminates in an annular flat head or flange 17 which has an accurately ground flat face. The remainder of the housing which forms the device comprises a series of flat plates or discs of substantially the same size as the flange 17. The adjacent or contact faces of the plates have accurately ground faces for fitting tightly together so as not to leak although no packing is interposed between them.

65 A housing disc 18 fits against the face of the head 17 and is provided with a pumping cylinder 19 formed therein, concentric with the shaft 7. A piston rotor 20 is provided within the cylinder 19 and is rigidly secured to the shaft 7 by a key 21.

70 As most clearly shown in Fig. 7 the rotor 20 has one portion, A, formed on a radius whose center is B, this radius being the same as the radius of the cylinder 19, as shown

by the dotted line C. The remainder or major portion of the rotor is formed on a lesser radius whose center is D. The portion A of the rotor will therefore fit tightly against the inner wall of the cylinder 19 and the length of such portion is greater than the distance between the shoulders 22 and 23 which bound each side of the combined intake and discharge opening to the cylinder, so as to overlap both of the shoulders at the same time. With this arrangement the rotor itself acts as a positive valve to prevent the fluid from the discharge line from shooting back around the rotor into the intake line when pumping high pressures.

The housing disc 18 is drilled transversely in registry with the ports 4 and 5 and one face thereof is cut away to provide passageways 24 and 25 which lead from the ports 4 and 5 respectively to an opening 26 which communicates with the cylinder 19 at one side thereof, and which is bounded by the shoulders 22 and 23.

Improved means are provided for separating the intake and discharge lines within the opening 26 and comprise a swingable arm 27 which has a relatively large pivotal bearing in the disc 18. The arm 27 carries a bearing member 28 pivotally mounted in the free end thereof which contacts with the rotor 20. The bearing member 28 has an arcuate face which is ground to fit that part of the rotor face which has the smaller radius, and the length of such face is less than the distance between the shoulders 22 and 23, so as to provide passageways for the fluid to enter and be discharged from the cylinder.

A laterally projecting lug 29 is formed on the arm 27 and a compression spring 30 is provided which bears between said lug and the disc 18 for yieldingly urging the arm 27 and bearing member 28 toward the rotor 20. By reason of the pivotal mounting of the member 28 in the arm 27, the plane of the arcuate contact face of the member 28 is perpendicular to the radius of the rotor at all times, thereby securing a very satisfactory sealing contact with the periphery of the rotor regardless of the swinging movement of the arm 27 caused by rotation of the rotor 20.

A second pumping unit is also provided and is of identical construction except that the rotor is keyed to the shaft 7 in diametrically opposite position; that is, the keyway therein is cut at a position 180 degrees from the position of the other. In the present embodiment two pumping units are illustrated but several such units may be assembled in like manner preferably with the positions of the rotors on the shaft spaced apart equal distances so as to impart minimum pulsations to the discharged fluid.

35 The second unit comprises a disc or plate

31, rotor 32, contact member 33, swinging arm 34 and compression spring 35. The two units are spaced apart by a separator plate 36 which preferably carries an annular bearing 37 keyed to the shaft 7.

An end plate 38 is secured against the outer face of the second unit and said plate, both pumping units and the separator plate 36 are all held in assembled relation against the face of the flange 17 by a series of cap screws 39. The contacting faces of these plates or discs are all ground to fit without leakage and the thickness of the moving parts; that is, the rotors, contact members, and swinging arms are ground a trifle thinner than the plates they work in so that working clearance is secured when assembled.

In the modification shown in Figs. 5, 6 and 8 the separator plate 36 has a slot there-through and an elongated flat spring 40 is rockably mounted therein with its opposite ends yieldably bearing against the swinging arms 27 and 34. The medial part of the spring 40 has a transversely extending bowed portion 41 for fitting over a rounded portion of the separator plate to provide a rocking pivot for the spring.

The spring 40 is subject to very little flexing due to the fact that when one of the swinging arms moves in one direction the other arm moves in the opposite direction.

It has been found that when the pump is required to lift its intake fluid a considerable distance such as when it is lifting 15 to 20 inches of vacuum, the fluid drawn into the pumping cylinder is at a considerably less pressure than the fluid in the discharge side of the pump, particularly where the pump is putting up a high pressure such as 75 to 100 pounds. At the time the rotor moves to the position where the entrapped fluid in the pumping cylinder comes in communication with the discharge side of the line, the fluid in the discharge side which is under high pressure will flow into the pumping cylinder at a very rapid rate and regardless of the carefulness of construction of the pumping parts this action will cause a metallic knocking in the pump.

This objection has been overcome and the problem solved by drilling a small by-pass 42 through the wall of the cylinder where it is closely adjacent to the discharge port 5 as shown most clearly in Fig. 2 of the drawings. This by-pass permits a small amount of fluid to flow from the discharge side of the pump into the pumping cylinder in advance of its opening into the discharge side of the line so that the pressure within the cylinder is gradually raised to substantially the same pressure as the pressure of the discharge side. By reason of this flow through the by-pass, the flow from the discharge side of the pump into the cylinder is practically

entirely eliminated and noiseless operation is secured.

In the operation of this improved form of pump the reduced portion 8 of the shaft 7 is connected with any suitable source of power and intake pipe 2 connected to a source of fluid supply. Rotation of the shaft 7 causes the rotors 20 and 32 to move within their respective cylinders. With each rotation of the shaft a quantity of the fluid is trapped within the rotor cylinder and carried around from one side of the bearing contact members 28 to the other side thereof and discharged out through the port 5 and discharge pipe 3.

Due to the fact that that portion of the rotor A, formed on a radius which is the same as the radius of the pumping cylinder, is of greater extent than the distance between the shoulders 22 and 23, the rotor itself acts as a positive valve for preventing fluid from the discharge port passing back around the rotor into the intake port.

The compression springs 30 and 35 in the preferable embodiment or the spring 40 in the modified form urge the swingable arms 27 and 34 toward the rotor so as to cause the bearing members 28 and 33 to have sealing contact with the outer peripheral surface of the respective rotors. As soon as pressure has been built up on the discharge side of the pump, said pressure also tends to urge the arms towards the rotors so that the pivoted bearing members form sealing contact with the rotor at all times. The arcuate faces of the bearing members 28 and 33 are always perpendicular to the radii of their respective rotors due to their pivotal mounting in their respective swinging arms.

In pumping high pressures a certain amount of the fluid seeps along the shaft 7 toward the end thereof which extends without the housing. This seepage is entrapped in the sump 13 and drained back into the intake side of the pump through the passageways 14 and 16.

Although but one specific embodiment of this invention and one modification thereof have been herein shown and described, it will be understood that numerous details of the constructions shown may be altered or omitted without departing from the spirit of this invention as defined by the following claim.

55 I claim:

A device of the class described comprising a housing having a pair of pumping cylinders therein arranged in axial alignment, a partition wall separating said cylinders, a shaft journaled on said housing and extending through said cylinders, rotors rigid on said shaft and disposed within said cylinders each of said cylinders having an opening at one side thereof communicating with discharge and supply ports, swingable

arms disposed in said openings for separating said discharge and supply ports, one end of each of said arms being pivoted to said housing and the other end thereof fitting against said rotors and an elongated spring extending through an opening in said partition wall with the ends thereof bearing against said arms for yieldingly urging them into sealing contact with their respective rotors.

In testimony whereof I have hereunto set my hand at Grand Rapids, Michigan, this 1st day of September, 1928.

JOHN B. TEESDALE.
